His Attorney.

UNITED STATES PATENT OFFICE

2,011,361

AUTOMATIC RECLOSED CIRCUIT
BREAKER SYSTEMRichard A. Hammond, Kansas City, Mo., assignor
to General Electric Company, a corporation of
New York

Application March 31, 1934, Serial No. 718,428

7 Claims. (Cl. 175—294)

My invention relates to automatic reclosing circuit breaker systems and particularly to such systems in which a circuit breaker is arranged to be opened in response to a predetermined abnormal condition on the circuit controlled by the circuit breaker and particularly to such systems in which the circuit breaker is arranged to be reclosed a predetermined number of times with predetermined time intervals between successive reclosures, if the abnormal condition causing the opening of the circuit breaker is of a permanent character.

An object of my invention is to provide an arrangement whereby in such an automatic reclosing circuit breaker system the control of the opening of the circuit breaker by the abnormal circuit condition is varied in accordance with the number of times the circuit breaker has been opened and reclosed. For example, in some cases it is desirable to have the first opening of the circuit breaker effected immediately upon the occurrence of a predetermined abnormal condition and after the first reclosure of the circuit breaker to have any subsequent opening of the circuit breaker effected in response to said predetermined abnormal condition only after the circuit breaker has remained closed for a predetermined time.

My invention will be better understood from the following description, when taken in connection with the accompanying drawing, the single figure of which diagrammatically illustrates an automatic reclosing circuit breaker system embodying my invention, in which the first reclosure occurs immediately after the first opening thereof and the subsequent reclosures occur only after the circuit breaker has remained open for a relatively longer period of time, and the scope of my invention will be pointed out in the appended claims.

Referring to the drawing, 1 represents a suitable circuit breaker, examples of which are well known in the art, for connecting a grounded supply circuit 2, which may be supplied from any suitable source, to a load circuit 3. As shown in the drawing, the circuit breaker 1 is of the well-known latched-in type and comprises a closing coil 4, which, when energized, closes the circuit breaker 1, a latch 5 for holding the circuit breaker in its closed position and a trip coil 6 which, when energized, releases the latch 5 and allows the circuit breaker to open.

Suitable fault responsive means, examples of which are well known in the art, are provided for effecting the opening of the circuit breaker

1. As shown in the drawing, the fault responsive means includes three over-current relays 7, 8 and 9 which are respectively connected in series relation with different phases of the supply circuit 2, and an instantaneous ground fault relay 50 and a time delay ground fault relay 51 which are connected in any suitable manner, examples of which are well known in the art, so that they are operated by a ground on any phase conductor of circuit 3 when circuit breaker 1 is closed. The relays 7, 8 and 9 are provided with instantaneous contacts 10, 11 and 12, respectively, and time delay contacts 10', 11' and 12' respectively. Each of these relay contacts is connected in series with the trip coil 6 and the auxiliary contacts 13 on the circuit breaker 1 so that an energizing circuit for the trip coil 6 is completed to effect the opening of the circuit breaker when the current in any phase of the supply circuit 2 exceeds a predetermined value. While I have shown each of the relays 7, 8 and 9 as having both instantaneous and time delay contacts in order to simplify the disclosure, it is obvious that in practice a separate over-current relay may be provided, if desired, to control each of these contacts.

The relays 50 and 51 are provided with contacts 52 and 53, respectively, which are connected in series with each other and in series with the trip coil 6 so as to effect the opening of the circuit breaker 1 when a ground fault occurs on the circuit 3.

For effecting a single instantaneous reclosure of the circuit breaker 1 after the initial opening thereof in response to an abnormal load condition on the load circuit, a control device 15 is provided which, as shown in the drawing, comprises two electromagnets 16 and 17 and a latch 18 being arranged to be tripped by the magnet 16 when it is energized. Under normal operating conditions the magnet 17 is held in its energized position by the latch 18 and in that position the contacts 19, 54 and 55 are closed and the contacts 20 and 21 are open. Also under normal operating conditions the magnet 16 is deenergized so that its contacts 22 and 23 are open.

The winding 24 of the magnet 16 is connected in series with the normally closed contacts 19 and the auxiliary contacts 25 on the circuit breaker 1 when it is open so that, as soon as the circuit breaker 1 opens, the magnet 16 is energized to close its contacts 22 and 23 and also to trip the latch 18 so that the contacts 19, 54 and 55 are opened and the contacts 20 and 21 are closed. The closing of the contacts 23 completes a lock-

ing circuit for the winding 24 of the magnet 16 so that it remains energized, after the opening of the contacts 19, until the circuit breaker 1 closes and opens its auxiliary contacts 25. The closing of the contacts 22 and 23, which are connected in series, completes an energizing circuit for a control relay 26 which, in turn, completes an energizing circuit for the closing coil 4 of the circuit breaker 1. As soon as the circuit breaker 1 closes, 5 the magnet 16 becomes deenergized and opens its contacts 22 and 23. Since the contacts 19 are now open, the original energizing circuit for the winding 24 of the magnet 16 is open and, therefore, the magnet 16 cannot be energized again 10 until the winding 27 of the magnet 17 is energized to effect the closing of the contacts 19. Consequently, if the circuit breaker 1 should open immediately after its first reclosure, the circuit breaker is prevented from being reclosed there- 15 after for a predetermined time. Suitable means are provided, as will be hereinafter described, for effecting the energization of the winding 27 of the magnet 17 if the circuit breaker 1 is still closed at the expiration of a predetermined time 20 interval after a reclosure thereof.

In order to effect the reclosing of the circuit breaker 1 a predetermined number of times with relatively long predetermined time intervals between successive reclosures in case the circuit breaker does not remain closed after the initial 30 instantaneous reclosure, and in order to limit the number of such time delayed reclosures, a suitable motor-operated reclosing device 27', examples of which are well known in the art is provided. As shown in the drawing, this reclosing device comprises a timer 28 and a substantially constant speed driving motor 29 therefor, which is permanently connected to a suitable source of current such as the supply circuit 2. The motor 30 is normally prevented from rotating by a stop 30 which engages a projection 31 on the timer 28. The stop 30 is arranged to be moved out of engagement with the projection 31 by a release magnet 32 when it is energized. The winding of the magnet 32 is connected in series with the contacts 21 of magnet 17 and contacts 33 of the control relay 26 so that when relay 26 is energized, to effect the initial reclosure of the circuit breaker 1, it also effects the energization of the release 40 magnet 32 to start the reclosing device 27' into 45 operation. In certain cases contacts 33 may be omitted from this circuit.

The timer 28 is provided with two sets of contacts 34 and 35 which are arranged to be closed successively, as the timer rotates, with predetermined time intervals between successive closures thereof. The contacts 34 and 35 are also arranged so that only one set can be closed at any instant. When the contacts 34 are closed, a circuit is completed for a control relay 36 associated with the timer 28 if at the same time the circuit breaker 1 is open so that its auxiliary contacts 25 are closed. The relay 36, when energized, completes a locking circuit for itself so that the relay remains energized when the contacts 34 are subsequently opened. When the contacts 35 are closed and the relay 36 is also energized at the same time, a circuit is completed for the control relay 26 to establish an energizing circuit for the closing coil 4 of the circuit breaker 1.

After the timer 28 has been in operation for a predetermined time and the contacts 34 and 35 have been closed a predetermined number of times, the timer is arranged to interrupt the connection between contacts 39 and 40 and to

establish a connection between contacts 39 and 41. If the circuit breaker 1 is closed at the time the contacts 39 and 41 are connected together, a circuit is completed for the winding 27 of the magnet 17 so as to restore it to its energized or normal position in which position it is held by the latch 18. If, however, the circuit breaker is open at the time the contacts 39 and 41 are connected together, the magnet 17 remains deenergized and no further automatic reclosing of the 10 circuit breaker can take place until after a suitable manual operation, such as the movement of the magnet 17 to its energized position, has been performed.

In order that circuit breaker 1 may initially 15 open instantly upon the occurrence of a ground fault and only after a predetermined time interval if the ground fault still exists after the first reclosure, I connect the normally closed contacts 54 of the magnet 17 in parallel with the contacts 53 of the time delay ground relay 51. Therefore, if the ground fault still exists after the first reclosure, the next opening of the circuit breaker 1 is not effected until sufficient time has elapsed to allow relay 51 which is calibrated to respond 25 substantially to the same value of ground current as relay 50 to close its contacts 53.

Also, in order that the circuit breaker 1 may be initially opened instantly upon the occurrence of a predetermined abnormal value of current in 30 any phase conductor of the circuit 3 when the circuit breaker 1 is closed and only after a predetermined time interval if the abnormal circuit condition still exists after the first reclosure, I connect the normally closed contacts 55 of the 35 magnet 17 in series with the parallel-connected instantaneous contacts 10, 11 and 12 of the over-current relays 1, 8 and 9 respectively. Therefore, after the initial reclosure of the circuit breaker 1, the instantaneous contacts 10, 11 and 12 of the 40 protective devices 1, 8 and 9 respectively cannot again effect the immediate opening of the circuit breaker 1 until the magnet 17 is resorted to its normal position.

The operation of the arrangement shown in 45 the drawing is as follows: When the circuit breaker 1 is closed, it is held in its closed position by the latch 5 as long as conditions on the load circuit are normal. When an abnormal condition, such as a ground fault, occurs which causes one 50 or more of the protective relays, such as the ground relay 50, to close its contacts instantly, a circuit is then immediately completed, through the auxiliary contacts 13 on the circuit breaker and the contacts of the operated relay, for the 55 trip coil 6 to effect the immediate opening of the circuit breaker 1. As soon as the circuit breaker 1 opens, its auxiliary contacts 25 complete, through the contacts 19 of the magnet 17 and the contacts 39 and 40 of the timer 28, an energizing 60 circuit for the winding 24 of the magnet 16. By closing its contacts 23, the magnet 24 completes, independently of the contacts 19, a locking circuit for its winding so that the magnet 16 is not deenergized by the subsequent opening of the 65 latter contacts. The energization of the magnet 16 also trips the latch 18 so that the magnet 17 moves to its deenergized position and in so doing opens its contacts 19, 54 and 55 and closes its contacts 20 and 21. As soon as the contacts 20 70 are closed, an energizing circuit is completed for the control relay 26 through the contacts 22 of the energized magnet 16 and the contacts 39 and 40 of the timer 28. By closing its contacts 43, the control relay 26 completes a circuit for the 75

closing coil 4 to close the circuit breaker 1. By closing its contacts 33 the control relay 26 also completes, through the contacts 21 of the magnet 17, an energizing circuit for the release magnet 5 32 of the reclosing device 27'.

When the circuit breaker 1 closes, the circuit of the winding 24 is interrupted at the auxiliary contacts 25 so that the magnet 16 becomes de-energized and opens its contacts 22 and 23. Since 10 the magnet 17 is now in its deenergized position, the contacts 19 thereof are open so that, if the circuit breaker 1 should open after its first reclosure, the magnet 16 is prevented from effecting another instantaneous reclosure.

15 Also since the contacts 54 of the magnet 17 are now open, it is evident that if the abnormal condition, which it was assumed was a ground fault, is still connected to the circuit 3 after the instantaneous reclosure of the circuit breaker 1, this ground fault will not effect the subsequent opening of the circuit breaker 1 until after the circuit breaker has remained closed for a sufficient length of time to allow the time delay ground fault relay 51 to close its contacts 53 in parallel 20 with the open contacts 54.

25 As soon as release magnet 32 of the reclosing device 27' is energized in response to the initial opening of the circuit breaker 1, the timer 28 starts to rotate and after it has been in operation 30 for a predetermined length of time, it closes the contacts 34. If at that time the circuit breaker 1 is open, a circuit is completed through the auxiliary contacts 25 on the circuit breaker 1, the winding of relay 36, contacts 34 and the contacts 35 39 and 40 of the timer 28 to effect the energization of the relay 36. Relay 36 by closing its contacts 44 completes, independently of the contacts 34, a locking circuit for its operating winding so that the relay remains energized after the timer 28 40 opens its contacts 34.

45 When the timer 28 subsequently closes its contacts 35, a circuit is completed for the control relay 26. This circuit includes contacts 45 of the relay 36 and contacts 35, 44, 40 and 39 of the timer 28. The control relay 26 then effects, in the manner above described, the energization of the closing coil 4 so as to close the circuit breaker 1. The control relay 26 also effects the energization 50 of the release magnet 32 which, however, has no effect at this time because the timer 28 is not in its normal position.

55 If following this reclosure the circuit breaker 1 should open again, the timer 28, in the manner above described, effects another reclosure of the circuit breaker a predetermined time after the previous reclosure.

60 After the timer 28 has successively closed and opened its contacts 34 and 35 a predetermined number of times, it disconnects contact 39 from contact 40 and then connects contact 39 to contact 41. If the circuit breaker 1 is closed at this time, a circuit is completed through the contacts 39 and 41 and the auxiliary contacts 46 on the circuit breaker 1 for the winding 27 of the magnet 17. The magnet 17 is then restored to its normal 65 position in which position it is held by the latch 18. The instantaneous ground relay 50 is now operative again to effect the immediate opening of the circuit breaker 1.

70 The contacts 39 and 40 are disconnected from each other at this time by the timer 28 in order to prevent "pumping" of the circuit breaker 1 in case a permanent fault should occur while the contacts 39 and 41 are connected together. It is 75 obvious that if a permanent fault should occur

while the contacts 39, 40 and 41 are all connected together, the circuit breaker 1 would be instantaneously reclosed in a manner above described after each opening thereof and would be opened immediately after each reclosure. By having the contacts 40 disconnected from the contact 39, such pumping of the circuit breaker cannot occur because the circuit of the magnet 16 is opened while the closing circuit for the magnet 17 is completed.

10 After the contacts 39 and 41 have been connected together for a sufficient length of time to effect the restoration of the magnet 17 to its normal position, the timer 28 disconnects the contact 39 from the contact 41 and again connects the 15 contact 39 to the contact 40. The timer 28 then returns to its normal position where it is stopped by the projection 31 engaging the stop 30.

15 If the abnormal condition which causes the circuit breaker to open is an abnormal current 20 which operates one of the over-current relays, such for example as the relay 7, the initial closing of the instantaneous contacts of this over-current relay completes through normally closed contacts 55 of magnet 17 a circuit for the trip coil 6 to 25 effect the immediate opening of the circuit breaker 1. After the first reclosure of the circuit breaker any subsequent operation of an over-current relay while the magnet 17 remains in its deenergized position does not effect the opening 30 of the circuit breaker until sufficient time has elapsed for the over-current relay to close its time delay contacts.

30 While I have, in accordance with the patent statutes, shown and described my invention as 35 applied to a particular system and as embodying various devices diagrammatically indicated, changes and modifications will be obvious to those skilled in the art and I, therefore, aim in the appended claims to cover all such changes and 40 modifications as fall within the true spirit and scope of my invention.

35 What I claim as new and desire to secure by Letters Patent of the United States, is:—

1. In combination, an electric circuit, a circuit 45 breaker in said circuit, means responsive to a predetermined abnormal condition of said circuit for controlling the opening of said circuit breaker, means responsive to the opening of said circuit breaker for effecting the reclosure thereof, and 50 means for causing said abnormal circuit condition responsive means to control the opening of said circuit breaker in one predetermined manner prior to a predetermined opening of said circuit breaker and in a different predetermined 55 manner after said predetermined opening of said circuit breaker.

2. In combination, an electric circuit, a circuit 60 breaker in said circuit, means responsive to a predetermined abnormal condition of said circuit for controlling the opening of said circuit breaker, means responsive to the opening of said circuit breaker for effecting the reclosure thereof, and means for causing said abnormal circuit condition responsive means to control the opening of said 65 circuit breaker in one predetermined manner prior to the initial opening thereof and in a different predetermined manner after the initial reclosure thereof.

3. In combination, an electric circuit, a circuit 70 breaker in said circuit, means responsive to a predetermined abnormal condition of said circuit for controlling the opening of said circuit breaker, means responsive to the opening of said circuit breaker for effecting the reclosure thereof, and 75

means for causing said abnormal circuit condition responsive means to effect the immediate opening of said circuit breaker prior to the initial opening thereof and to effect the opening thereof 5 of after a predetermined time interval subsequent to the initial reclosure thereof.

4. In combination, an electric circuit, a circuit breaker in said circuit, means responsive to a predetermined abnormal condition of said circuit 10 for effecting the opening of said circuit breaker at two different time intervals after an occurrence of said abnormal condition, means responsive to the opening of said circuit breaker for effecting the reclosure thereof, and means responsive to a predetermined opening of said circuit 15 breaker for rendering said abnormal condition responsive means inoperative to effect a subsequent opening of said circuit breaker at one of said time intervals after the occurrence of said 20 abnormal condition.

5. In combination, an electric circuit, a circuit breaker in said circuit, means responsive to a predetermined abnormal condition of said circuit for effecting the opening of said circuit breaker 25 at two different time intervals after an occurrence of said abnormal condition, means responsive to the opening of said circuit breaker for effecting the reclosure thereof, and means responsive to the initial opening of said circuit breaker for 30 rendering said abnormal condition responsive means inoperative to effect a subsequent opening of said circuit breaker at the shorter of said time intervals.

6. In combination, an electric circuit, a circuit breaker in said circuit, means responsive to a predetermined abnormal condition of said circuit for effecting the immediate opening of said circuit breaker and the opening of said circuit breaker after a predetermined time interval upon the occurrence of said predetermined abnormal condition, means responsive to the opening of said circuit breaker for effecting after a time interval 10 the reclosure thereof, a relay for rendering said opening means inoperative to effect an immediate opening of said circuit breaker and means responsive to the initial opening of said circuit breaker for effecting the operation of said relay. 15

7. In combination, an electric circuit, a circuit breaker in said circuit, means responsive to a predetermined abnormal condition of said circuit for effecting the immediate opening of said circuit breaker and the opening of said circuit breaker after a predetermined time interval upon the occurrence of said predetermined abnormal condition, means responsive to the opening of said circuit breaker for effecting after a time interval 20 the reclosure thereof, a relay for rendering said opening means inoperative to effect an immediate opening of said circuit breaker and means responsive to the initial opening of said circuit breaker for effecting the operation of said relay for a predetermined time so that during said predetermined time the opening of said circuit 25 breaker is controlled by said time delay opening means. 30

RICHARD A. HAMMOND.
